UNITED STATES PATENT OFFICE.

ELLSWORTH M. LETTS, OF WAVERLY, NEW YORK, ASSIGNOR OF FORTY-NINE ONE-HUNDREDTHS TO CHARLES C. ANNABEL, OF WAVERLY, NEW YORK.

BOTTLE-CAPPING DEVICE.

1,401,800.

Specification of Letters Patent. Patented Dec. 27, 1921.

Application filed August 7, 1920. Serial No. 401,939.

To all whom it may concern:

Be it known that I, ELLSWORTH M. LETTS, a citizen of the United States, and residing at Waverly, Tioga county, State of New York, have invented certain new and useful Improvements in Bottle-Capping Devices, of which the following is a specification.

The present invention relates to bottle capping tools for applying metal caps of the type having a corrugated flange adapted to be contracted around the top shoulder or head of a bottle.

The principal objects of the invention are to provide a tool which requires little physical exertion to actuate so that it may be operated by women; to provide a tool which may be easily operated with one hand; to provide a tool operated by grasping two handles in the hand and forcing them toward each other; to provide a tool which is constructed so that the parts which engage the bottle to hold it against movement do not injure, crack or break the bottle; and to provide a tool having yielding means to start the parts on their return movements after a capping operation.

Other objects and features of novelty will be apparent from the description taken in connection with the drawings, in which—

Figure 1 is a side elevation of a tool constructed in accordance with the present invention showing the parts in the positions which they occupy when the cap has been pressed home on the top of the bottle;

Fig. 2 is a side elevation, parts being shown in section;

Fig. 3 is an end view; and

Fig. 4 is a sectional view taken substantially on the line 4-4 of Fig. 1.

Referring to the drawings the numeral 10 indicates the main member of the tool. As clearly shown in Fig. 4, one end thereof is formed with a notch 11 which is adapted to receive the neck of a bottle just below the shoulder 12 thereof, the shoulder preventing upward movement of the member relative to the bottle. The other end 13 of the member is made in the form of a handle and a lever 14 is disposed substantially parallel therewith and has a part also in the form of a handle. Thus the lever handle 14 and the handle 13 of the member may be grasped

by the operator's hand, as indicated in Fig. 1, for the purpose of actuating the device. 55 The lever 14 is pivoted on a pin 15 and acts on a second lever 16. This latter lever is pivoted on the pin 17 carried by a pair of spaced ears 18 on the member 10. One end of the lever 16 carries a cap applying cup 60 19. Preferably this cup is swivelly supported on the lever 16, as indicated at 20, so that it may adjust itself during the cap applying movement. The cap which this tool is adapted to apply is of the well known 65 type having a corrugated flange adapted to be contracted around the head of the bottle, so it is merely necessary to force the cup 19 down over the cap, the rim of the cup acting to contract the corrugated flange of 70 the cap and thus secure it on the top of the bottle.

As previously stated the lever 14 is adapted to act on the lever 16. In the form of the invention shown, the connection between these two levers consists of a toggle mechanism comprising the link 21 hinged both to the end of the lever 16 and to the short arm 22, the latter being rigid with the lever 14 and being disposed in a slot 23 in 75 the member 10. Because of the two levers and the toggle mechanism, the force applied at the handle 14 is transmitted to the cap applying cup and very greatly increased in amount. Consequently it requires little 80 physical exertion to apply a cap with the present tool. In order that the toggle mechanism may not swing by its dead center position, the lever 14 is disposed so that it strikes the bottom of the member 10 as indicated at 24, when the cup has been depressed the full amount of its movement, the toggle links being disposed so that they do not quite reach dead center position when the handle 14 strikes the abutment 24. 90

If the member 10 or the parts thereof engaging the shoulder 12 of the bottle are of cast iron or a similar hard metal, it is found that if there are any defects in the glass of the shoulder, the neck will be broken or 100 cracked. According to the present invention this difficulty is eliminated. To this end at least the parts of the tool which engage the shoulder 12 are constructed of a material which will not injure the same. 105 It is found that aluminum is very satis-

factory for this purpose. As shown the legs 25 forming the notch 11 are provided on their upper surfaces with the wear plates or pads 26 of aluminum, these plates being secured to the legs by screws 27. In order to hold the wear plates against lateral movement, as viewed in Fig. 3, the legs 25 may be provided with flanges 28. In this case the screws 27 merely act as means to hold the wear plates in position and do not take any substantial strain.

It will be observed for the proper application of the cap to the bottle it is desirable that the corners of the wear plates 26 engage the shoulder of the bottle be definitely positioned with respect to the cap applying cup when the latter is in its final position. With the present tool the plates 26 may be adjusted to and from the cup by the insertion or removal of spacers or shims 29.

When one corner of the wear plates 26 becomes mutilated or injured, the wear plate may be turned around to present a fresh corner. As there are eight corners or edges which may be utilized it is apparent that the life of the wear plate is very great.

If desired a yielding means may be provided which is compressed when the cap is applied and will exert a force to open up the tool when the actuating force is removed therefrom. As shown the bottom of the cap applying cup is provided with a rubber disk 30. When the cap is applied to the bottle this disk is compressed and when the grip on the handles 14 and 13 is loosened, this rubber disk expands thereby starting the parts back to their open positions. Primarily this yielding means is desired so as to start the toggle device away from dead center.

In the operation of the device a cap is placed on top of a bottle and the bottle placed with its neck in the notch 11 of the tool, the tool being held in one hand of the operator. Now by gripping the handles 13 and 14 and forcing them together, the cup 19 will be forced down over the cap, thus applying it to the bottle. When the grasp on the handle is released, the rubber washer 30 will expand thereby breaking the toggle away from its dead center position shown in Fig. 1.

It will be seen that the present tool is constructed so that the actuating force is greatly multiplied, thus furnishing a tool by means of which bottles may be capped by women. Furthermore there is practically no breakage in the operation because of the construction of the parts which engage the shoulder on the neck of the bottle.

Although a specific embodiment of the invention has been described in detail, it is to be understood that the invention is not thus limited but includes modifications and changes which come within the scope of the appended claims.

Having thus described the invention what is claimed as new and desired to be secured by Letters Patent is:

1. A bottle capping device including in combination, a member adapted to straddle the neck of the bottle below the shoulder thereon, a lever pivoted intermediate its ends on one side of said member and having a cap applying cup at one end thereof, actuating means hinged to said member on the side opposite to the cup carrying lever.

2. A bottle capping device including in combination, a member formed with a notch to receive the neck of a bottle below the shoulder thereof, a cap applying cup, means so connecting said cup to said member as to permit movement of said cup to apply the cap, means to move the cup to force the cap on the bottle including toggle mechanism and means to actuate said mechanism, said last means being hinged to said member on the opposite side to said cap applying cup.

3. A bottle cap applying device including in combination, a member having a notch adapted to tightly receive the neck of the bottle below the shoulder thereon, a lever pivoted intermediate its ends on said member and having a cap applying cup at one end thereof, and an actuating lever pivoted on the opposite side to said first lever on said member and link connection from one end of said actuating lever to the end of the first lever opposite the cup end to force the cup toward the top of the bottle.

4. A bottle cap applying device including in combination, a member having a notch adapted to tightly receive the neck of the bottle below the shoulder thereon, a lever pivoted intermediate its ends on said member and having a cap applying cup at one end thereof, and an actuating lever pivoted on the opposite side to said first lever on said member and link connection from one end of said actuating lever to the end of the first lever opposite the cup end to force the cup toward the top of the bottle, said actuating lever having a handle part disposed substantially parallel with said member whereby said handle and member may be grasped by the hand and the handle moved toward the member to operate the device.

5. A bottle capping tool including in combination, a member adapted to engage a bottle and coöperating therewith to be held against movement toward the top of the bottle, a cap applying device, an actuating lever carried by the member, and a second lever pivotally connected to said member on the side opposite to said actuating lever and operatively connected to the cap applying device and toggle mechanism connecting said levers.

6. A bottle capping tool including in combination, a member adapted to engage a bottle and coöperating therewith to be held

- against movement toward the top of the bottle, a cap applying device, a lever pivoted to said member and carrying said cap applying device, an actuating lever pivoted to said member, toggle arm connection between said levers, said actuating lever having a handle part substantially parallel with said member whereby the member and said part may be grasped to operate the tool.
- 5 7. A cap applying tool including in combination, a member adapted to receive the neck of a bottle below the shoulder thereof, wear plates on said member adapted to engage said shoulder, said plates being composed of a material which is softer and more yielding than that of said member, and means associated with said member to force a cap on the top of the bottle.
- 10 8. A cap applying tool including in combination, a member adapted to receive the neck of a bottle below the shoulder thereof, wear plates on said member adapted to engage said shoulder, said plates being composed of aluminum, and means associated with said member to force a cap on the bottle.
- 15 9. A cap applying tool including in combination a member adapted to straddle the neck of a bottle below the shoulder thereof, a pair of wear plates on said member disposed on opposite sides of the neck and adapted to rest on the parts of said member on opposite sides of the bottle neck and to engage said shoulder with one edge, said plates having a plurality of straight edges and being adjustably secured to said member whereby the plates may be turned to present a fresh edge to the shoulders of the bottles.
- 20 10. A cap applying tool including in combination a member adapted to straddle the neck of a bottle below the shoulder thereof, a pair of aluminum wear plates on said member disposed on opposite sides of the neck and adapted to engage said shoulder, said plates being adjustably secured to said member whereby the plates may be turned to present a fresh edge to the shoulders of the bottles.
- 25 11. A bottle cap applying tool including in combination, a member adapted to receive a bottle and hold it against movement when the cap is applied, a pair of levers on said member one operative on the other and a cap applying cup hinged for free swinging movement to one of said levers.
- 30 12. A cap applying tool including a member bifurcated at one end with legs closely adjacent the bottle neck on opposite sides below its shoulder, the said legs having along their outer margins opposite the bottle neck flanges, wear plates having straight edges on opposite sides detachably secured on said legs with one straight edge abutting the flange and the opposite straight edge closely adjacent the bottle neck below the shoulder
- 35 and adapted to engage the shoulder, the said wear plates being reversible on their supports to bring different edges into working position to engage the shoulder.
- 40 13. A bottle capping tool including in combination a body member formed as a handle at one end and as an open jaw at the other end adapted to receive the neck of a bottle below its shoulder and engage its shoulder, a pair of oppositely positioned flanges on said jaw, a pair of wear plates with a plurality of engaging edges, one of said edges on each plate adapted to abut against one of said flanges, while another edge is in position to contact with the bottle neck, shims under said plates for adjusting their height and retaining screws for the plates; whereby the plates may be turned to present a fresh edge for contact when needed.
- 45 14. A bottle capping tool including in combination a body member formed as a handle at one end and as an open jaw at the other end adapted to receive the neck of a bottle below its shoulder and engage the shoulder, an operating lever having a hinge connection at one end to and below said body member and having a portion extending therefrom along said handle and adapted to be grasped in the hand of the user along with the handle and to move on its hinge toward or away from said handle, a shorter lever pivoted between its ends to and above said body member between the end of said operating lever and the jaw of the body portion, a cap applying cup hinged to and hanging from the end of said second mentioned lever next to and above the jaw, and means for transmitting upward pressure on the other end of said second lever to force the cap downward by and through the turning of said operating lever toward the handle as by the pressure of the hand drawing the handle and lever together.
- 50 15. A bottle capping tool including in combination a body member formed as a handle at one end and as an open jaw at the other end adapted to firmly engage the shoulder on the neck of a bottle, an L-shaped operating lever hinged at its bend to the underside of said body member, the body member having an aperture through which the short leg of said operating lever protrudes upwardly, a two armed lever hinged between its ends to the upper side of said body member, a toggle joint connection between said short leg and one arm of said two-armed lever, and a cap applying cup hinged to the other arm of said two-armed lever.
- 55 16. A bottle capping tool including in combination a body member formed as a handle at one end as an open jaw at the other end adapted to firmly engage the shoulder on the neck of a bottle, and L-shaped operating lever hinged at its bend to the

underside of said body member, the body member having an aperture through which the short leg of said operating lever protrudes upwardly, while the longer arm 5 thereof is movable to or from a position substantially parallel to the handle of the body member, a two-armed lever hinged between its ends to the upper side of said body member and extending along the same from one

end above said short leg to a position above 10 the top of the bottle at its other end, means for transmitting power from the end of said short leg to the end portion of the arm of the two-arm lever which is above it, and a cap applying cup hinged to the other arm of said two-armed lever.

In testimony whereof I affix my signature.
ELLSWORTH M. LETTS.
